METHYLOLATED QUATERNARY AMMONIUM COMPOUNDS

Peter L. de Benneville and Leo S. Luskin, Philadelphia, Pa., assignors to Rohm & Haas Company, Philadelphia, Pa., a corporation of Delaware

No Drawing. Application December 4, 1953,
Serial No. 396,306

7 Claims. (Cl. 260—249.9)

This invention relates to methylolated quaternary ammonium compounds, particularly in the form of salts, which serve as anti-static agents on textiles, particularly on synthetic fibers which are prone to develop and retain a static charge. These compounds may be assigned the general structure

as typical thereof. In this formula R represents hydrogen or an alkyl group up to four carbon atoms, preferably the methyl group, R⁰ represents hydrogen or an ROCH₂— group, R¹ and R² represent alkyl groups individually or when taken together represent a saturated divalent aliphatic chain which forms a five- to six-sided heterocycle with the nitrogen, as in morpholine, thiamorpholine, 3,5-dimethylmorpholine, pyrrolidine, piperidine, or N-methylpiperazine, R³ represents an aliphatic hydrocarbon group, including alkyl, alkenyl, and aralkyl groups, X represents an anion, and R⁴ and X together may represent a propiobetaine radical, —CH₂CH₂COO—.

There have long been sought materials which could be applied to textile fibers, particularly to synthetic fibers, including those from cellulose acetate, nylon, polyester condensates, polyacrylonitrile, and other polymeric fiber-forming materials to serve as anti-static agents which would have some resistance to normal cleaning processes and which would not cause objectionable changes in the character of these fibers. A group of compounds meeting this challenge has now been discovered. These new compounds have the property of imparting a charge or conducting layer on fibers, yarns, and fabrics treated therewith and apparently thus dissipate static charges or prevent the accumulation of static charges thereon. These compounds might be expected to form insoluble resins. Yet they do not appear to do so. Rather they appear to react with the fibers. At least resinification of the compounds has not been forced beyond the water-soluble stage. Yet these novel compounds are sufficiently retained on yarns and fabrics after these are washed to continue to exert anti-static action.

Various aminoacetoguanamines are known of the formula

2

These are conveniently prepared by reacting together in the presence of an alkaline reagent dicyandiamide and a tert-aminoacetonitrile

10 Such compounds are known in which R¹ and R² are alkyl, aralkyl, cycloalkyl, alkenyl, and phenyl. The two R groups may be the same or may be different. The two R groups may also be part of a saturated divalent chain, such as —CH₂CH₂CH₂CH₂—,

20 to form a heterocycle with the amino nitrogen. These aminoacetonitriles are formed in the same way as those from other secondary amines, such as dimethylamine, diethylamine, dibutylamine, dodecylmethylamine, and the like. Secondary amine, formaldehyde, and hydrogen cyanide are brought together in any convenient order and reacted. The tert-aminoacetonitrile is collected as a residue or is purified by a conventional step, such as distillation.

30 It is reacted with dicyandiamide in the presence of an alkaline catalyst, such as sodium or potassium hydroxide, benzyltrimethylammonium or dibenzylidimethylammonium hydroxide, choline, or a quaternary ammonium alkoxide, such as choline methoxide or benzyltrimethylammonium butoxide. A volatile, inert organic solvent may be used and the reaction accomplished by heating under reflux. The product may be collected as a residue and purified by extraction, charcoaling, crystallizing, or similar conventional step.

35 The tert-aminoacetoguanamine which is thus formed is reacted with an alkylating agent to form a quaternary ammonium salt. Typical alkylating agents include methyl iodide, methyl bromide, ethyl bromide, ethyl chloride, methyl sulfate, butyl bromide, octyl bromide, dodecyl bromide, octadecyl bromide, allyl chloride, methallyl chloride, crotyl chloride, dodecetyl chloride, benzyl chloride or bromide, methylbenzyl chloride, butylbenzyl chloride, octylbenzyl chloride, dodecylbenzyl chloride, methyldodecylbenzyl chloride, pentadecylbenzyl chloride, etc. In place of one or more of the above alkylating agents of the more usual type there may be used β -propiolactone.

45 55 The tert-aminoacetoguanamine and alkylating agent may be mixed and heated together directly or, preferably, in the presence of an organic solvent, such as an alcohol, an aromatic hydrocarbon, nitroparaffin, or other non-reactive, volatile solvent, typical of which are methanol, ethanol, isopropanol, butanol, benzene, toluene, xylene, nitromethane, acetonitrile, and formamide. Reaction is desirably effected by heating under reflux and may be continued until tests show a high proportion of ionizable halide, sulfate, or other anion.

60 65 One of these anions may be replaced with another anion through metathesis or through known procedures for replacing anions of quaternary ammonium salts. Thus there may appear as an anion not only the common halide or methyl sulfate ions, but also sulfate, acetate, formate, nitrate, phosphate, and other anions.

70 On the other hand there may in effect be introduced directly a kind of organic ion by reacting the tert-amino-

acetoguanamine with β -propiolactone. This reaction gives propiobetaines,

10

Solvent is usually driven off from the reaction mixture to give a solid, which is essentially the desired quaternary ammonium salt.

15

This may be used as obtained or may be purified, if desired, by extraction or crystallization. These salts have fairly good anti-bacterial properties. For example, the lauryldimethylguanaminomethylammonium bromide has a phenol coefficient of 85 against *Micrococcus pyogenes*, while substitution of the methyldodecylbenzyl group for the lauryl group gives a salt having a coefficient of 125.

The quaternary salts are reacted with formaldehyde to give N-hydroxymethyl derivatives. The formaldehyde may be supplied from the usual aqueous formaldehyde solutions of commerce, from a revertible polymer, or from alcoholic solutions. One or both of the NH₂—groups of the quaternary compound may be reacted and sufficient formaldehyde is supplied to accomplish the desired degree of methylation. The methylation reaction is best carried out at a pH between 7 and 10. Temperatures between 40° and 100° C. may be used. The reaction products are soluble, particularly in water. The solutions can be evaporated to give solid products which have the characterizing group —NHCH₂OH. From one to two such groups may be introduced. There is some evidence that more than two groups may be introduced on average.

This group may be converted to an ether group by reacting the methylol derivatives with an alcohol. This is done by heating the methylol compound with an alcohol under acidic conditions, usually at a pH of 5 to 3, most conveniently under reflux conditions with separation of water. The resulting ROC₂NH— derivative is obtained as a solution, from which it may be obtained as a solid by evaporating the solvent, usually here an excess of the alcohol used, such as methyl, ethyl, or butyl alcohol.

Typical preparations of compounds of this invention are described in the following illustrative examples, wherein parts are by weight unless otherwise designated.

Example 1

(a) A mixture of 55.4 parts of dimethylaminoacetonitrile, 50.4 parts of dicyandiamide, and 80 parts of isopropanol is stirred and heated under reflux (about 87° C.). Over a 45 minute period there are added to this mixture 32.3 parts of a 47% choline methoxide solution in methanol in 43.7 parts of isopropanol. The resulting mixture is stirred and heated under reflux for five hours. It is then cooled. The guanamine thus formed is filtered off and dried in an amount of 77 parts. It may be purified with charcoal in boiling water and recrystallized therefrom. It then melts at 235°–238° C. and contains by analysis 49.9% of nitrogen (theory 50.0%).

Repetition of the above procedure with use of sodium hydroxide, potassium hydroxide, choline, or benzyltrimeth-

ylammonium hydroxide as catalyst leads to the same product in a like degree of purity.

The compound thus prepared corresponds in composition to dimethylaminoacetoguanamine, which may be represented

10

In the same way diethylaminoacetonitrile can be converted to diethylaminoacetoguanamine. Neither of these tert-aminoacetoguanamines is effective as an anti-static agent; nor are methylol derivatives thereof.

(b) There are mixed 29.6 parts of dimethylaminoacetoguanamine, 22.3 parts of benzyl chloride, and 680 parts of methanol. The mixture is heated under reflux for about 12 hours with formation of the quaternary salt, which separates when the mixture is cooled. This salt is filtered off. Additional product is obtained from the filtrate when it is concentrated. There is thus obtained in about 75% yield the quaternary salt,

20

This salt is sparingly soluble in water and is more soluble in aqueous dilute acid solutions. It is a white solid, melting at 251°–253° C.

Reaction of diethylaminoacetoguanamine with benzyl chloride in the same way leads to the diethyl benzyl acetoguanamino quaternary chloride which is essentially like the dimethyl derivative described above.

(c) A portion of 44 parts of this quaternary salt is treated with 38 parts of an aqueous 36.5% formaldehyde solution which has been brought to a pH of 9.3 by addition of 10% sodium carbonate solution. The mixture is slowly heated to about 80° C. with solution of the salt within 10 minutes to give a clear, orange-colored, viscous solution. Evaporation of this solution under reduced pressure at 45° C. gives a hygroscopic solid which by analysis contains 1.85 hydroxymethyl groups per molecule. This product is extremely water-soluble. This compound is fairly effective as a corrosion inhibitor. Rate of corrosion of a 10% sulfuric acid solution on an iron plate is reduced from over 0.25 lb./sq. ft./day to about 0.05 lb./sq. ft./day.

Methylation of the diethyl compound gives a very similar product.

The above procedure is followed using 44 parts of the above quaternary salt and 20 parts of the aqueous 36.5% formaldehyde solution adjusted to a pH of about 9.2. The solid obtained on evaporation shows on analysis about one methylol group per molecule.

(d) A solution is prepared from 8.3 parts of the above benzyl chloride quaternary salt of dimethylaminoacetoguanamine in 12 parts of methanol. Thereto is added a solution of 3.1 parts of methyl hemiformal in 5 parts of methanol which has been adjusted to a pH of 8.5. The resulting mixture is heated under reflux for about an hour, at which time the solution has become homogeneous. It is then cooled and brought to a pH of 3.5 by adding dilute acid. The acid solution is heated under reflux for 20 minutes, is then cooled, is neutralized, and is evaporated to incipient precipitation. The concentrate is diluted with 70 parts of water to give a solution containing 14% of the dimethoxymethylated quaternary salt.

5

When nylon cloth is passed through a dilute solution of this salt and is dried, no static charge is built up thereon. If the cloth is now washed with soap and soda ash solution, a charge can be imparted, but it is largely dissipated in 10 seconds.

In the same way ethanol, propanol, or butanol solutions of formaldehyde may be used to give the corresponding alkoxyvinyl methyl derivatives.

Example 2

(a) A mixture of 40 parts of dimethylaminoacetoguanamine, 59 parts of dodecetyl chloride

and 1000 parts of methanol is heated under reflux for five hours. The solution is then concentrated and cooled. There separates a white solid in an amount of .84 parts. It has a melting point of 249° C. and contains by analysis 9.62% of chlorine. It corresponds in composition to the dodecetyl chloride quaternary salt of dimethylamino-guanidine. The theoretical chlorine content of this salt is 9.57%.

(b) There are mixed 57 parts of this salt and 35 parts of formaldehyde in an aqueous 37% solution which has been adjusted with sodium carbonate to a pH of 9.5. The mixture is heated to about 80° C. for 20 minutes and treated with 800 parts of benzene. Benzene and water are distilled off to give a clear solution. The resulting solution is evaporated to give a slightly colored solid which is the di-hydroxymethyl derivative. It is freely soluble in water and quite surface active. Applied to synthetic fabrics, it prevents accumulation of a static charge. It reacts with cellulosic fabrics to supply quaternary groups thereon.

Example 3

(a) A mixture of 16.8 parts of dimethylaminoaceto-guanamine, 31 parts of dodecyl bromide, and 238 parts of methanol is heated under reflux for 20 hours, at which time the quaternization is over 90% complete, as shown by titrations for ionizable chlorine. When the reaction mixture is cooled, a solid separates and is filtered off. When dried, it melts at 243°-245° C. with decomposition and contains 19.0% of bromine. Evaporation of the filtrate gives an additional crop of solid quaternary salt, bringing the yield to 42.2 parts. The product is soluble in water and in dilute acids. The solutions are markedly surface active. This salt has a phenol coefficient against *Salmonella typhosa* of 25 and against *Micrococcus pyogenes* var. *aureus* of 85.

(b) A portion of 11.6 parts of this salt is treated with 7 parts of aqueous 36.5% formaldehyde solution adjusted to pH 9. The mixture is heated to about 75° C. and treated with 160 parts of benzene. Heating is continued with azeotropic removal of water. Evaporation leaves 10.5 parts of a tan solid, which is the polymethylol derivative, containing by analysis 15.6% of bromine.

This compound is converted to the methoxymethyl derivative by treating with methanol acidified to a pH of 3.5 and heating with toluene. This compound is also effective in dissipating electric charges on synthetic yarns and fabrics.

Example 4

(a) There are mixed 8.4 parts of dimethylaminoaceto-guanamine, 19.1 parts of methyldodecylbenzyl chloride, and 120 parts of methanol. The mixture is heated under reflux for six hours. Solvent is evaporated to leave a gummy solid which is triturated with ethyl acetate, which is filtered off and evaporated to give a yellow wax which melts at 204°-209°C. It corresponds in composition to the methyldodecylbenzyl chloride quaternary of dimethylaminoacetoguanamine. This substance is sparingly soluble in water to give strongly surface-active solutions.

(b) There are mixed 9.6 parts of the above quaternary and 3.5 parts of aqueous 36% formaldehyde solution which has been adjusted to a pH of 9.3 with soda ash.

6

The mixture is heated and about 80 parts of benzene added. The mixture is heated under reflux and then water and benzene are taken off to give a solid residue which is soluble in water, the dimethylolated derivative.

5. The alkoxyethyl derivatives are formed by reacting the methylol compound as above on the acid side with an alkanol.

Example 5

(a) There are mixed 16.8 parts of dimethylaminoacetoguanamine, 36.7 parts of n-octadecyl bromide, and 317 parts of methanol. The mixture is heated under reflux for 21 hours. During this time the initial slurry becomes homogeneous and then deposits a white solid. The reaction mixture is cooled to give a white, waxy solid, which is filtered off, washed with ether, and dried in a yield of about 33 parts by weight. It contains by analysis 15.3% of bromine and corresponds to the octadecyl bromide quaternary ammonium salt, for which the theoretical bromine content is 15.9%. The compound melts at 242°-244° C.

(b) There are mixed 25 parts of the above quaternary ammonium salt, 17 parts of aqueous 36% formaldehyde solution which has been adjusted to pH 9 with soda ash solution, and 300 parts of toluene. The mixture is heated under reflux and is then distilled. The residual solution is evaporated under reduced pressure to a tan solid. It is somewhat soluble in water and imparts surface activity to its solutions.

Example 6

(a) A solution of 23.5 parts of dimethylaminoaceto-guanamine in 250 parts of water is added to 7.2 parts of β -propiolactone. A clear solution results. It is stirred and heated at 80° C. for five hours. It is evaporated to dryness to give a white solid which is soluble in dimethyl-formamide or ether. The solid melts at 218°-222° C. with decomposition. By nitrogen analysis it contains 91% of the quaternary salt, guanaminomethyl dimethyl pro-piobetaine.

(b) A mixture of 12 parts of this product, 56 parts of methanol, 5.6 parts of a 59% formaldehyde solution in methanol, and 2.5 parts of water is adjusted to a pH of 8.0-8.5 with aqueous 50% sodium hydroxide solution. This mixture is heated under reflux for 30 minutes, acidified, and heated for 20 minutes under reflux. It is neutralized, cooled, and filtered. The filtrate is evaporated to dryness to give 21.5 parts of solid product, the di-

methoxymethyl derivative of the above quaternary compound. It is dissolved in water to give a 15% solution. This solution is added to a treating bath through which a fabric of synthetic fiber from polyacrylonitrile is passed to give a finish which prevents accumulation of static charges.

Instead of the reaction of guanaminomethyl dimethyl propiobetaine with formaldehyde and methanol, it may be reacted with aqueous formaldehyde solution to yield hydroxymethylated derivatives having one to two HOCH_2- groups per molecule. The resulting compound may be represented.

Rayon twill was impregnated with solutions of methoxymethyl derivatives of above quaternary ammonium compounds. The impregnated fabrics were then heated at about 150° C. and washed. The treated fabrics possessed definite ion exchange properties with capacities for various samples ranging from 3×10^{-4} to 10^{-3} milliequivalents per square centimeter. Some samples were treated

with benzyl chloride. They then had capacities of 4×10^{-3} and 9×10^{-3} milliequivalents per square centimeter. The ion exchange compounds formed by reaction of the methoxymethyl derivatives and cellulose were found regenerable. The treated fabrics withstood attack by alkali whereas untreated samples of the same fabric were markedly deteriorated by this treatment. The treated fabrics are of interest in filter cloths, conveyor belts, and the like for handling pulps and slurries from which small amounts of acid are to be removed.

Cellophane sheets were treated as above to give films having ion exchange action with a moderate degree of permselectivity.

Example 7

(a) To a solution of 179 parts of morpholine in 174 parts of water are added 20 parts of concentrated hydrochloric acid, and then at 15° – 20° C. 163 parts of a 37% solution of formaldehyde in water. Following this there is introduced 54 parts of anhydrous hydrogen cyanide at 15° – 20° C. and the mixture stirred for two to three hours at 20° C. The resulting crystalline product is recrystallized from ethanol to yield 63 parts of morpholinoacetonitrile, melting at 59° – 61.5° C.

(b) When 63 parts of this aminonitrile, 37.8 parts of dicyandiamide and 85 parts of isopropyl alcohol are heated under reflux, and a solution of 14 g. of potassium hydroxide in 50 ml. of isopropyl alcohol is added to this over a period of one hour, the solution darkens and the dicyandiamide dissolves. After refluxing for five hours and cooling, the dark red product is collected on a filter, washed with small amounts of hot water and dried. The tan solid so obtained is high-melting and corresponds in analysis to morpholinoacetoguanamine.

(c) A mixture of 21 parts of the tertiary guanamine and 14 parts of methyl iodide in 100 parts of methanol is heated for three hours. After removal of solvent the water-soluble quaternary salt is obtained in good yield as a solid residue.

(d) To 12 parts of 36.5% formaldehyde solution in water is added sufficient 10% aqueous sodium carbonate to give a pH of 9.3. When 17.5 parts of the above quaternary salt are added and the mixture is warmed at 80° C. for ten minutes, there results a clear solution of the methylol derivative. The water may be removed by azeotroping with benzene to give the solid methylol derivative, or the solution may be used without isolation. The composition of the product corresponds to about three methylol groups per mol of quaternary guanamine.

In a similar way, from N-cyanomethylpyrrolidine, which is obtained as a liquid distilling at 80° – 83° C./15 mm., there can be prepared, using essentially the same ratios of reactants, pyrrolidinoacetoguanamine. This can be used in exactly the same way as heretofore described to produce methylolated and methoxymethylated quaternary guanamine salts.

We claim:

1. Compounds of the structure

wherein R represents a member of the class consisting of hydrogen and alkyl groups of not over four carbon atoms, R⁰ represents a member of the class consisting of hydrogen and the ROCH₂— group, R¹ and R² when taken individually represent alkyl groups of not over 12 carbon atoms and when taken together represent a saturated divalent aliphatic chain which forms a five- to six-sided heterocycle with the indicated nitrogen from the class consisting of

10
5

morpholine, thiamorpholine, pyrrolidine, and piperidine, R³ represents a member of the class consisting of alkyl, alkenyl of at least three carbon atoms, benzyl, and alkyl benzyl groups and jointly with X a propiobetaine radical, and X represents a salt-forming anion.

2. A compound of the formula

3. A compound of the formula

4. A compound of the formula

5. Compounds of the structure

wherein R is a member of the class consisting of hydrogen and the methyl group and X is a member of the class consisting of chlorine and bromine.

6. A compound of the formula

7. A compound of the formula
